US00D685510S

(12) **United States Design Patent**
Henry et al.

(10) **Patent No.:** **US D685,510 S**
(45) **Date of Patent:** **** Jul. 2, 2013**

(54) **FLASHLIGHT**

(75) Inventors: **Louis F. Henry**, Scarsdale, NY (US);
Bruce Ancona, New York, NY (US);
Jacob Wilson, New York, NY (US)

(73) Assignee: **Blackbeam LLC**, New York, NY (US)

(**) Term: **14 Years**

(21) Appl. No.: **29/400,932**

(22) Filed: **Sep. 2, 2011**

(51) **LOC (9) Cl.** **26-05**

(52) **U.S. Cl.**
USPC **D26/60**

(58) **Field of Classification Search**

USPC D26/60, 61, 63–66, 28, 29, 36, 37–40,
D26/44, 46; 362/191, 197–199, 396, 473–478
